(57) **CLAIM**

The ornamental design for an electrode pad, as shown and described.

DESCRIPTION

FIG. 1 is a perspective view of an electrode pad embodying our new design;

FIG. 2 is top view thereof;

FIG. 3 is bottom view thereof;

FIG. 4 is a side view thereof;

FIG. 5 is another side view thereof;

FIG. 6 is a front view thereof;

FIG. 7 is a back view thereof; and,

FIG. 8 is a perspective view thereof in a state of use.

The broken lines shown in FIGS. 1-3 depict portions of the electrode pad that form no part of the claimed design. The additional broken lines shown in FIG. 8 depict environmental subject matter and form no part of the claimed design.

1 Claim, 6 Drawing Sheets
